UNITED STATES PATENT OFFICE.

W. BARNET LE VAN, OF PHILADELPHIA, PENNSYLVANIA.

DESIGN FOR GOVERNOR-BASE.

Specification forming part of Design No. **6,374**, dated January 28, 1873.

To all whom it may concern:

Be it known that I, W. BARNET LE VAN, of the city and county of Philadelphia, in the State of Pennsylvania, have invented and produced a new and original Design for a Governor-Base for Steam-Engines, of which the following is a specification:

The nature of my design is fully represented in the accompanying drawing of a governor-base—

Figure 1 being a vertical central section at the line $x\ x$ of Fig. 3; Fig. 2, a similar section at the line $y\ y$ of Fig. 2; Fig. 3, a horizontal section at the line $z\ z$ of Fig. 1.

To construct a governor-base in accordance with my design, I provide a globular casing, A, having a horizontally-projecting flange or nozzle, B, for the attachment of the steam-supply pipe, and a valve-seat, C, for a screw-stop valve,

concentric with which is a flange or nozzle, D, to receive the nut of said valve. A belt or passage, F, encircles the casing A, having partitions E at top, forming a seat for a two-ported governor-valve, the passage F serving to conduct the steam from the governor-valve to the engine. Upper and lower flanges A^1 and A^2 are provided for attachment to the governor and the engine, respectively.

What I claim as my invention is—

A design for a governor-base for steam-engines, composed of a globular casing, encircled by a steam-passage, and provided with seats for the stop and governor valves, as described and shown.

W. BARNET LE VAN.
